UNITED STATES PATENT OFFICE.

HERMAN NIELSEN, OF BROOKLYN, NEW YORK.

ROTARY ENGINE.

SPECIFICATION forming part of Letters Patent No. 720,952, dated February 17, 1903.

Application filed June 30, 1902. Serial No. 113,795. (No model.)

To all whom it may concern:

Be it known that I, HERMAN NIELSEN, a citizen of the United States, and a resident of the city of New York, borough of Brooklyn, in the county of Kings and State of New York, have invented a new and Improved Rotary Engine, of which the following is a full, clear, and exact description.

The object of the invention is to provide a new and improved rotary engine which is simple and durable in construction, very effective in operation, and arranged to utilize the motive agent to the fullest advantage, to permit convenient reversing, and to allow of cutting off the steam at any desired point of the piston-stroke to use the steam expansively.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a longitudinal sectional elevation of the improvement on the line 1 1 of Fig. 3. Fig. 2 is a transverse section of the same on the line 2 2 of Fig. 3. Fig. 3 is a plan view of the same. Fig. 4 is an enlarged end elevation of the stopping, starting, reversing, and cut-off lever. Fig. 5 is an enlarged inverted plan view of the steam-valve, showing the admission-port; and Fig. 6 is a plan view of the steam-valve, showing the exhaust-port.

The improved rotary engine is mounted on a suitably-constructed frame A, having ball-bearings B, having a cylindrical casing C, in which is mounted to rotate a wheel D, having its hub D' provided with a plurality of radially-disposed cylinders D², D³, D⁴, and D⁵, as plainly illustrated in Fig. 2. The wheel D is arranged eccentrically in the casing C, and in the several cylinders D², D³, D⁴, and D⁵ are mounted to reciprocate the pistons E E' E² E³, having their outer ends rounded off and in frictional contact with the inner surface of the rim of the cylindrical casing C, as plainly indicated in the drawings. The hub D' of the wheel D is secured on an annular bearing F', formed on a hollow shaft F, jour-

naled on ball-bearings B', carried by the main frame A, eccentric to the ball-bearings B, as shown in Fig. 1. One outer end of the shaft F is the inlet for the motive agent and the other the outlet for the exhaust, and the said inlet end of the shaft F fits into a head G, connected by a pipe H with a boiler or other source of motive-agent supply. The other end of the shaft F connects with a head I, having an exhaust-pipe J for conducting the exhaust motive agent to the outside.

Within the hollow shaft F is arranged a valve K, formed with a transverse partition K', dividing the interior of the valve K into the inlet-compartment K² and the outlet-compartment K³, the said inlet-compartment K² being in communication with the inlet end of the shaft F and the outlet-compartment K³ being in communication with the exhaust end of the shaft F. The inlet-compartment K² is provided with a port b, adapted to register with ports a, formed in the shaft F and the hub D' and leading into the cylinders E, E', E², and E³, as plainly shown in Fig. 2, the said ports a being also adapted to register with an exhaust-port c, likewise formed in the valve K, but leading into the outlet-chamber K³. One end of the valve K is provided with a valve-stem K⁸, extending through a suitable stuffing-box in the head G, and outside thereof on the outer end of this stem K⁸ is secured a lever K⁴, having a horizontal extension K⁵, reaching under the segmental flange G² on the head G. (See Figs. 1 and 4.) The extension K⁵ is provided with stop-collars K⁶ K⁷ to limit the longitudinal sliding movement of the extension K⁵ necessary to bring the valve K in the desired cut-off position, as hereinafter more fully described.

By reference to Fig. 5 it will be seen that the admission-port b in the valve K is made in triangular shape, so that when the lever K⁴ is in an innermost position and the collar K⁶ abuts on the flange G², as shown in Fig. 1, then the base end of the said admission-port b is in register with one of the ports a, and consequently a large amount of steam can pass at a given time through the said ports b and a into the corresponding cylinder. By moving the lever K⁴ outwardly the valve K is moved in a like direction, and the base end of the admission-port b moves out of register

with a port *a* to cut off the steam from the corresponding cylinder. The exhaust-port *c* in the valve *K* is rectangular, as plainly indicated in Fig. 6, so that a full exhaust is had at all times from the cylinders at the time they move into an uppermost position and the ports *a* register with the said port *c*.

The heads *G* and *I* are held stationary and are supported by suitable rods *G'* and *I'*, respectively, from the frame *A*.

The operation is as follows: When the several parts are in the position illustrated in the drawings, then the motive agent entering the shaft *F* by way of the pipe *H* and head *G* 15 passes into the compartment *K*² and from the latter through the port *b* into the port *a* of the cylinder *D*⁴, then in a lowermost position—that is, the cylinder nearest the rim of the casing *C*. Now the steam passing into 20 this cylinder *D*⁴ at the inner end thereof presses against the piston *E*², so that the latter presses against the rim of the casing *C*, and as the latter and the wheel *D* are mounted eccentrically one to the other it is evident 25 that the force of the piston *E*² on the rim of the casing *C* causes the latter to rotate and with it the wheel *D*. From the foregoing it will be seen that the wheel *D* and the casing *C* rotate together and in the same direction by the action of the piston on the rim of the casing *C*. Now as the wheel *D* rotates the port *a* of the cylinder *D*⁴ finally moves out of register with the port *b*, so that the motive agent is cut off from this cylinder and the steam contained therein acts expansively to continue the rotary motion of both the wheel *D* and the casing *C*. At about the time the port *a* of the cylinder *D*⁴ is cut off from the port *b* the port *a* of the next following cylinder moves in register with the port *b*, so that live motive agent now passes into this next cylinder to again apply an impulse to the casing *C* and the wheel *D* in the manner above described relative to the cylinder *D*⁴ and its piston *E*². The rotary motion 40 of the wheel *D* finally brings the port *a* of the first cylinder *D*⁴ in register with the port *c*, so that the steam can now escape from the cylinder *D*⁴, by way of its port *a*, port *c*, and 45 chamber *K*³, into the exhaust end of the shaft *F* to the head *I* and exhaust-pipe *J* to the outside. This takes place at the time the piston *E*² moves into an uppermost position. It will be evident that by the operator turning the 50 lever *K*⁴ the valve *K* can be turned in the shaft *F* to bring the port *b* to one or the other side of the vertical plane extending through the axis of the shaft, so that the live steam can be conducted into the next adjacent cylinder to insure rotation of the casing *C* and wheel *D* in either direction. In order to limit the turning movement of the shaft *K*⁴ for the 55 purpose mentioned, I provide the flange *G*² with stops *G*³ *G*⁴, adapted to be engaged by the extension *K*⁵, previously referred to and shown in Fig. 4. The extension *K*⁵ between the collars *K*⁶ *K*⁷ is of such length relative to

the length of the admission-port *b* that when the lever *K*⁴ is pulled out until the collar *K*⁷ abuts against the flange *G*², then the apex 70 end of the port *b* is completely out of register with the port *a* of the cylinder then moving into working position. The motive agent is thus shut off from the ports *a* and the engine comes to a standstill. When the lever *K*⁴ is 75 in the position shown in full lines in Fig. 4, then the casing *C* and wheel *D* rotate in the direction of the arrow *a'*, and when the lever *K*⁴ is swung to the position shown in dotted 80 lines in the said Fig. 4, then the casing *C* and 85 the wheel *D* rotate in the inverse direction of the said arrow *a'*.

Having thus described my invention, I claim as new and desire to secure by Letters Patent—

85

1. A rotary engine comprising a cylindrical casing mounted to turn, a wheel within said casing and having a hollow shaft mounted to turn eccentrically relative to the said casing, the said wheel having a plurality of cylinders 90 disposed radially from the hub of the wheel, the inner ends of the cylinders having ports extending through the hub and shaft to the inside of the latter, pistons in the said cylinders, acting on the rim of the cylinder-casing, 95 and a valve mounted to slide and turn in the said hollow shaft, having compartments for connecting with the said ports leading to the cylinders, one of the compartments being connected with the motive-agent supply and the other with the exhaust, the admission-port in the said valve being triangular, as set forth.

2. A rotary engine comprising a cylindrical casing mounted to turn, a wheel within said casing and having a hollow shaft mounted to 105 turn eccentrically relative to the said casing, the said wheel having a plurality of cylinders disposed radially from the hub of the wheel, the inner ends of the cylinders having ports extending through the hub and shaft to the 110 inside of the latter, pistons in the said cylinders, acting on the rim of the cylinder-casing, a valve mounted to slide and turn in the said hollow shaft, having compartments for connecting with the said ports leading to the 115 cylinders, one of the compartments being connected with the motive-agent supply and the other with the exhaust, and a head on one end of the said hollow shaft, connected with the motive-agent supply, the said end of the 120 shaft opening into the said admission-compartment of the said valve, as set forth.

3. A rotary engine comprising a cylindrical casing mounted to turn, a wheel within said casing, having a hollow shaft mounted to turn 125 eccentrically relative to the said casing, the said wheel having a plurality of cylinders disposed radially from the hub of the wheel, the inner ends of the cylinders having ports extending through the hub and shaft to the 130 inside of the latter, pistons in the said cylinders, acting on the rim of the cylinder-casing, a valve mounted to slide and turn in the said hollow shaft, said valve having compart-

ments for connecting with the said ports leading to the cylinders, one of the compartments being connected with the motive-agent supply and the other with the exhaust, and manually-controlled means for sliding and turning said valve in the shaft, for cutting off the motive agent sooner or later, and for reversing the engine, as set forth.

4. A rotary engine comprising a cylindrical casing mounted to turn, a wheel mounted to turn eccentrically within the casing and having a plurality of cylinders disposed radially from the hub of the wheel, a hollow shaft carrying the said wheel and having ports connecting with ports in the inner ends of the cylinders, pistons mounted to slide within the said cylinders and in contact at their outer ends with the inner surface of the cylinder-casing, and a valve mounted to turn and to slide in the said hollow shaft to reverse the engine and to start and stop the same, the valve having an admission-compartment and an exhaust-compartment, provided with ports for connection with the shaft and cylinder-ports, as set forth.

5. A rotary engine comprising a cylindrical casing mounted to turn, a wheel mounted to turn eccentrically within the casing and having a plurality of cylinders disposed radially from the hub of the wheel, a hollow shaft carrying the said wheel and having ports connecting with the ports in the inner ends of the cylinders, pistons mounted to slide within the said cylinders and in contact at their outer ends with the inner surface of the cylinder-casing, and a valve mounted to turn and to slide in the said hollow shaft, the valve having an admission-compartment and an exhaust-compartment, provided with ports for connection with the shaft and cylinder-ports, the admission-port in the said valve being triangular in shape, as set forth.

6. In a rotary engine, the combination with a cylindrical casing mounted to turn, a wheel mounted to turn eccentrically in the casing and having a plurality of radially-disposed cylinders, pistons in the cylinders and engaging the casing, and a hollow shaft carrying the wheel and having ports connecting with the ports of the cylinders, of a compartment-valve mounted to slide and turn in the shaft, each compartment of the valve being pro-

vided with a port, means connected with the valve for turning and sliding the same, means for limiting the sliding movement of the valve, and means for limiting the turning movement of said valve, as set forth.

7. In a rotary engine, the combination with a revoluble casing, a plurality of revoluble cylinders eccentrically mounted in the casing, pistons in the cylinders and engaging the casing, and a hollow shaft upon which the wheels are mounted, of a compartment-valve mounted to slide in the shaft, each compartment being provided with a port, one of the ports being triangular, and means for sliding said valve, as set forth.

8. In a rotary engine, the combination with a revoluble casing, a plurality of revoluble cylinders eccentrically mounted in the casing, pistons in the cylinders and engaging the casing, and a hollow shaft carrying the cylinders, of a compartment-valve mounted to slide in the shaft, each compartment being provided with a port, a handle connected with the valve and provided with a horizontal extension having spaced stops, and a projection with which the stops of the extension are adapted to alternately engage, as set forth.

9. In a rotary engine, the combination with a revoluble casing, a plurality of movable cylinders eccentrically mounted in the casing, pistons in the cylinders and engaging the casing, and a hollow shaft carrying the cylinders and provided with ports, of a hollow valve mounted to slide and turn in the shaft and provided with compartments, each compartment of the valve being provided with a port, a handle connected with the valve and provided with a horizontal extension having spaced stops, and a flange at one end of the shaft and with which the said stops are adapted to alternately engage, said flange being provided with oppositely-projecting stops with which the extension of the handle is adapted to engage, as set forth.

In testimony whereof I have signed my name to this specification in the presence of two subscribing witnesses.

HERMAN NIELSEN.
